CLAIM

The ornamental design for a drawer pull, as shown and described.

DESCRIPTION

FIG. 1 is a front elevational view of the instant drawer pull; FIG. 2 is a top plan view;

FIG. 3 is a side elevational view thereof; and,

FIG. 4 is a bottom plan view thereof.

The showing of the balance of the drawer face, body and the pair of slides is included for the purpose of illustrating environmental structure only and forms no part of the claimed design.
